FLOYD HEAVENER, OF DENVER, COLORADO, ASSIGNOR TO HIMSELF AND
J. W. COLLINS, OF LARAMIE CITY, WYOMING TERRITORY.

CHAIR-BRACE.

SPECIFICATION forming part of Letters Patent No. 239,246, dated March 22, 1881.

Application filed September 9, 1880. (No model.)

To all whom it may concern:

Be it known that I, FLOYD HEAVENER, of Denver, in the county of Arapahoe and State of Colorado, have invented a new and Improved 5 Chair-Brace; and I do hereby declare that the following is a full, clear, and exact description of the same, reference being had to the accompanying drawings, forming part of this specification, in which—

10 Figure 1 is a side elevation; Fig. 2, an underneath view. Fig. 3 is a rear elevation.

The object of my invention is to provide a set of braces for a chair which shall hold the legs, back, and seat firmly together against 15 any tendency to loosen or become separated.

It consists in combining with the chair two wires running from the cross-bar of the back of the chair down through the seat, and thence to the front corners of the seat and up through 20 the same, over which wires two other wires are strained, which pass from the two hind legs to the two fore legs, as hereinafter more fully described.

In the drawings, A represents an ordinary 25 form of chair whose back is composed of a cross-bar at the top and rounds connecting the same to the seat. Through the cross-bar at the top of the back are run two wires, *a a*, which have heads at their upper ends, and 30 pass down the back on each side thereof and through the seat, underneath which they are twisted together to form an **X**, (see Fig. 2,) and then extended to the front corners of the seat, and up through the same to the 35 upper surface, where they are provided with heads. If, however, the chair be an arm-chair, these ends are not allowed to terminate at the seat, but extend up through the seat to the arms, in which arms the ends are held by 40 heads, as aforesaid. At the point *b*, where the two wires *a a* are twisted together beneath the seat, two other wires, *c c*, are twisted together to form an **X**, and looped over the part *b*, so as to strain the wires *a a* downwardly. 45 These wires *c c* have heads at their ends, and pass from the hind legs over the twisted por-

tion *b*, and then to the front legs, the heads of these wires being embedded on the outside surface.

In order to tighten the brace, the wires *c c* 50 are first laid across the section *b* and then twisted on each side of the same, and then, if necessary to keep the last two wires from untwisting, a piece of wire, *e*, is extended through the loops formed by the object which was used 55 to twist the wires. By means of this arrangement of wires it will be seen that the chair is braced in all directions, and there is no chance for any of the parts to become separated.

Having thus described my invention, what I 60 claim as new is—

1. The combination, with the back, seat, and legs of a chair, of the two wires *a a*, extending from the top of the back down through seat, and up again through the seat, and a 65 second pair of wires, *c c*, looped over the first-mentioned wires beneath the seat, and connecting the four legs of the chair, substantially as shown and described.

2. The combination, with the back, seat, and 70 legs of a chair, of the two wires *a a*, extending from the back down through the seat, and crossed and twisted to form sections *b*, and then fastened to the seat, and the two wires *c c*, also crossed and twisted and looped over 75 the section *b*, and connecting the four legs, as described.

3. The combination, with the legs, the seat, and the back of a chair, of four wires, twisted in pairs and connected together beneath the 80 seat of the chair, and having one set of ends extending downwardly to the four legs of the chair, and the other set of ends extended up through the seat and the back of the chair, substantially as described. 85

The above specification of my invention signed by me this 31st day of August, 1880.

FLOYD HEAVENER.
